UNITED STATES PATENT OFFICE.

EDWARD A. SYTZ, OF BROOKLYN, NEW YORK, ASSIGNOR TO MERGENTHALER LINOTYPE COMPANY, A CORPORATION OF NEW YORK.

SLUG-CASTING MOLD.

Application filed April 18, 1923. Serial No. 632,824.

To all whom it may concern:

Be it known that I, EDWARD A. Sytz, a citizen of the United States, residing at Brooklyn, in the county of Kings and State 5 of New York, have invented certain new and useful Improvements in Slug-Casting Molds, of which the following is a specification, reference being had therein to the accompanying drawing.

10 This invention relates to typographical casting machines, such as linotype machines of the general organization represented in U. S. Letters Patent to O. Mergenthaler, No. 436,532, wherein a typebar or slug is 15 cast in a slotted mold and up against a composed line of matrices which produce the type characters thereon. In these machines, the mold usually comprises four distinct parts, namely, a body portion, a cap portion, and right and left hand liners, these 20 parts defining the side and end walls of the mold slot. The liners are produced in various lengths and thicknesses and are selectively employed to vary the dimensions of 25 the mold slot according to the size of the slugs to be cast. However, for slugs of the larger sizes, such as those of the head-letter or display variety, the cap portion of the mold is ordinarily formed with a series of 30 tapered core sections in order to cast such slugs in skeleton form. In the use of a mold of this kind, it is essential that the liners register at their inner ends with the core sections, as otherwise the molten metal 35 will escape from the ends of the mold slot and produce an imperfect slug and lead to other more serious objections. Heretofore, to meet this condition, it has been customary to make the core sections of varying 40 sizes and to space them apart at irregular distances in accordance with certain definite lengths of liners. This practice, besides adding to the cost of manufacture, has given rise to many disadvantages in the use of the 45 mold. For instance, it has materially limited the number of liners which may be used (practically excluding those of odd and fractional dimensions) and has consequently restricted the range of adjustment of the 50 mold slot to a corresponding degree. Moreover, by reason of the small size and close spacing of some of the core sections, the tapering of the latter, which is desirable in facilitating the ejection of the slugs, 55 is so limited that oftentimes the slugs be-

come wedged in the mold and cause damage to the parts.

The present invention is intended to obviate the foregoing objections and contemplates a construction which will permit the 60 use of liners of any desired lengths and which at the same time will enable the mold cap to be manufactured at less cost and with core sections having sufficient taper to provide for a smooth and easy ejection of 65 the cast slugs. To this end, specifically, the mold cap is mounted so as to be adjustable endwise relatively to the liners, the idea being to provide for the proper registration of the liners and core sections for any given 70 adjustment of the mold slot. Thus, if, in changing the length of the mold slot, a substitute liner should terminate at its inner end in the space between two adjoining core 75 sections, an endwise adjustment of the cap 75 in one direction or the other will bring the corresponding core section into proper registration with the liner and thereby prevent the escape of the molten metal from the end of the mold slot. By reason of this capability, there is no limitation as to the number of variant liners which may be employed in adjusting the mold, and further there is no restriction as to the width, spacing or tapering of the core sections, so long 80 as the range of adjustment of the mold cap is sufficient to perform the function above noted. In the present instance, and as preferred, the core sections are made of uniform size and are spaced apart at equal distances throughout the length of the mold 85 cap, due regard being had for a more pronounced tapering of the core sections. The exact construction and arrangement of the parts will be more fully set forth in the 90 detailed description to follow.

Referring to the drawings:

Figure 1 is a front or face view of the improved mold;

Fig. 2 is a sectional plan view taken on 100 the line 2--2 of Fig. 1;

Fig. 3 is a transverse vertical section taken on the line 3--3 of Fig. 1; and

Fig. 4 is a perspective view of a portion of 105 a slug cast in the improved mold.

As usual, the mold comprises a body portion A and a cap portion B which define the opposite side walls of the mold slot, and two intermediate liners C and D which define the opposite end walls of the slot. The 110

body portion A is fastened by screws or similar devices A¹ to the well known rotary disc E (shown in dotted lines), and, at its opposite ends, it is provided with upright posts or lugs A² passing through corresponding slots formed in the ends of the liners and the cap portion. The cap portion B is held in place by means of a pair of set screws E¹ carried by the disc E and which, when tightened up, clamp the cap portion tightly down upon the two liners. In the present instance, the cap portion is formed in its front face with a longitudinal groove B¹ and in its under face with a series of transverse grooves B², leaving blocks or core sections B³ projecting into the mold cavity proper. The two liners C and D are of the customary L-shape and formed with fore and aft tongues or ribs C¹ and D¹, respectively, which engage in corresponding grooves formed in the upper face of the body portion A. As the parts are thus constructed and arranged, by loosening the screws E¹, the liners C and D may be quickly removed and replaced by others to effect a change in the dimensions of the mold slot. To change the length of the mold slot only, it is merely necessary to remove the left hand liner C and substitute another of the required length, as the right hand liners do not ordinarily vary in length. The foregoing parts, except as hereinafter pointed out, are well known in the art and require no further description.

According to the present invention, the cap portion B is adjustable endwise in opposite directions relatively to the liners C and D, this being provided for by lengthening to the required extent the end slots wherein the posts A² engage. In effecting such adjustment of the cap portion, the screws E¹ are first loosened to release it and then tightened up to clamp it in its new position. By reason of this adjustability of the cap portion, the liners may be made of any desired lengths, whether in even or odd typographical units or fractions thereof. In the drawing, the cap portion is shown as shifted slightly to the right and with one of its core sections B³ in registry with the inner end of the liner C, so that the molten metal when injected into the mold cavity cannot escape. Let it be supposed, however, that the liner C were replaced by another of such length that its inner end would terminate in a vertical plane located between two adjoining core sections B³ or in one of the grooves B², as indicated by the dotted lines in Fig. 2. In such case, unless otherwise provided for, the molten metal would flow up into the groove and out beyond the end of the liner and thus produce on the slug an overhanging bar or fin which would interfere with the proper ejection of the slug and cause damage to the parts. In the present

construction, however, this condition is avoided, as the endwise adjustment of the cap portion will locate one or another of the core sections in proper registry with the inner end of the liner, as in Fig. 1. The advantage just mentioned would be present without regard to the form or arrangement of the core sections, but in the preferred embodiment illustrated, the core sections are larger and more widely spaced apart than heretofore, the size and spacing of said sections being made uniform throughout the length of the cap portion for purposes of economy in manufacture. As before, the core sections B³ are tapered both downwardly and forwardly so as to facilitate the ejection of the slug from the mold, but, in the present instance, the degree of taper has been materially increased, as permitted by the larger size and wider spacing of the sections. As a result, the tendency of the slugs to stick or adhere to the core sections because of the shrinkage of the metal during solidification is reduced to a minimum, it being found in practice that a comparatively light pressure is sufficient to dislodge the slugs from the mold. As a result, also, the slugs themselves are much stronger and better adapted to sustain the load imposed thereon during printing or stereotyping. Fig. 4 illustrates a portion of a slug cast in the improved mold, presenting as usual, a relatively thin body portion F, an overhanging face portion or shelf F¹ and a series of transverse ribs F² projecting from the body portion and giving support to the overhanging shelf. As will be observed, however, the ribs F² are of uniform size and equally spaced apart like the grooves B² in which they are cast, and furthermore, said ribs are thicker where they join the body portion F and overhanging shelf F¹, due to the increased taper of the core sections B³ or to the greater flare of the transverse grooves B² incident to such increased taper.

It is old in prior constructions to adjust the cap portion endwise, but such adjustment has been made to vary the length of the mold slot, involving a corresponding adjustment of one of the end walls of the mold. In the present construction on the other hand, the adjustment of the cap portion is not intended and actually does not change the length of the mold slot, the cap portion being adjustable relatively to the end walls of the mold to insure the proper cooperation between the said walls and the core sections.

In the accompanying drawings, the invention has been shown merely in preferred form and by way of example and as applied to a specific kind of mold, but obviously many changes and alterations may be made therein and in its mode of application without departing from its spirit. Thus, the adjustable cap portion would also be useful in

connection with non-adjustable molds, as when such molds are made with slots of different lengths and it is desired to use a cap portion common to all. Again, the cap portion, instead of being integral as shown, might be divided horizontally in two sections, one fixed and the other adjustable, and the latter formed with core sections; or the core sections might be supported in any other suitable manner, so long as they are capable of being adjusted endwise of the mold slot for the purpose set forth. It should be understood, therefore, that the invention is not limited to any specific form or embodiment except in so far as such limitations are specified in the claims.

Having thus described my invention, what I claim is:

1. A slug casting mold comprising side and end walls, one of the side walls being adjustable endwise relatively to the end walls.
2. A slug casting mold comprising side and end walls, one of the side walls being provided with core sections and adjustable endwise relatively to the end walls.
3. A slug casting mold comprising a body portion, a cap portion, and intermediate liners, the cap portion being adjustable endwise relatively to said liners.
4. A slug casting mold comprising a body portion, a cap portion formed with core sections, and intermediate liners, the said cap portion being adjustable endwise relatively to said liners.

5. A slug casting mold adjustable as to the length of the mold slot and comprising side and end walls, one of the side walls being adjustable endwise relatively to the end walls for any given length of the mold slot. 40

6. A slug casting mold adjustable as to the length of the mold slot and comprising side and end walls, one of the side walls being formed with core sections projecting into the mold slot and adjustable endwise relatively to the end walls to insure the proper cooperation between the core sections and the end walls for any given length of the mold slot. 45

7. A slug casting mold comprising side 50 and end walls and having core sections projecting into the mold slot, the said core sections being mounted with a capacity for adjustment endwise of the mold slot independently of the end walls to insure the proper 55 cooperation between said parts.

8. A slug casting mold comprising side and end walls, one of the side walls being adjustable endwise relatively to the end walls and provided with core sections of uniform size throughout. 60

9. A slug casting mold comprising side and end walls, one of the side walls being adjustable endwise relatively to the end walls and provided with core sections spaced 65 apart at equal distances throughout the length of the mold.

In testimony whereof, I have affixed my signature hereto.

EDWARD A. SYTZ.
